UNITED STATES PATENT OFFICE

2,489,392

COIL FORM MOUNTING

Frank Wood, Elmhurst, Ill., assignor to Zenith
Radio Corporation, a corporation of Illinois

Application April 26, 1946, Serial No. 665,049

6 Claims. (Cl. 248—361)

1

The present invention pertains in general to coil form mountings and in particular to an improved mounting arrangement wherein a coil form mounting member is formed as an integral part of a radio receiver chassis or the like.

In the past, coil forms, such as those used in radio receivers, have generally been mounted by means of twist or spade lugs which are riveted to the coil form and pass through openings in the chassis to which the coil form is secured by twisting the lugs or threading nuts thereon.

It is an object of the present invention to provide an improved mounting arrangement which eliminates the need for attaching lugs or the like to the coil form, whereby more economical manufacture of apparatus employing such coil forms is obtained through elimination of certain manufacturing operations and reduction of coil form spoilage occurring therein.

A further object of the invention is to provide an improved arrangement for securing a coil form to a chassis of sheet material without the need for any securing means which extends through the chassis, whereby greater freedom in mounting parts on the side of the chassis opposite the coil form is obtained.

The features of the present invention which are believed to be novel are set forth with particularity in the appended claims. The present invention itself, both as to its organization and manner of operation, together with further objects and advantages thereof, may best be understood by reference to the following description taken in connection with the accompanying drawing in which:

Figures 1, 2 and 3 disclose one method of forming a mounting member, or lug, from a chassis of sheet material in accordance with one embodiment of the invention.

Figure 4 is a perspective view of a coil form mounted by means of the member, or lug, disclosed in Figures 1 to 3.

Figures 5 and 6 are elevational views of coil forms mounted in accordance with modifications of the invention.

Figures 7 and 8 disclose an alternative form of mounting member.

Figures 9 and 10 disclose side and elevational views, respectively, of a further modification of the invention, and

Figure 11 discloses an alternative form of the mounting members disclosed in the preceding figures.

In the embodiment of the invention illustrated in Figure 4 there is shown a portion of a chassis

2

1 of sheet metal or the like, from which a mounting member, or lug, 2 has been formed perpendicular and parallel to the plane of the chassis. The parallel portion of the lug 2 extends through opposed slots in a tubular coil form 3. The openings are preferably diagonally opposed when the coil form is cylindrical. The free end of lug 2 is formed over to engage the coil form 3, thereby securing it firmly in place.

10 It is preferred that the mounting lug 2 be formed from a sheet metal chassis in order to simplify manufacturing operations and to obtain the utmost economy in manufacture. Figure 1 discloses an outline which is die-cut in a sheet metal chassis 1. The die is preferably arranged also to form the cut away portion along the dotted lines of Figure 1 into the shape disclosed in Figures 2 and 3. Coil form 3 is passed over the portion of lug 2 which is parallel to the chassis 1 until the coil form engages a shoulder formed near the fixed end of the lug 2, as illustrated in Figure 4. The free end of lug 2 is then formed perpendicular to the plane of the chassis 1 in order to prevent movement of coil form 3 relative thereto. The free end of the lug 2 preferably has a weakened neck portion 4 formed therein so that it may readily be formed over without damage to the coil form.

While chassis for radio receivers and the like 30 are generally made of sheet metal, the invention is not limited to the use of such material. For example, the chassis may be molded of a phenolic resin in which case mounting members, such as 2, may be molded therein. When the mounting members are formed of material which is not 35 ductile a dab of cement or the like may be applied to the tip thereof, after the coil form has been placed thereover, rather than bending the tip of the mounting member.

40 The cantilever portion of the mounting member need not be parallel to the chassis. In Figure 5 there is shown a section of a supporting sheet or chassis, 5 having a mounting member 6 formed therefrom, which member is formed 45 closer to the chassis 5 at the free end of the member than at the fixed end thereof. A coil form 7, having diagonally opposed openings therein which are spaced at different distances from one 50 end thereof, is placed over the cantilever portion of member 6 by springing the latter away from the chassis. After the coil form has been placed over the mounting member, it is allowed to spring back in place to press the lower end of coil form 7 firmly against the chassis 5. The slope of member 6 may be relied on to prevent movement of

coil form 7 relative thereto, or, if desired, a dab of cement 8 or the like may be applied to the tip of member 6.

In Figure 6 there is shown a section of supporting sheet, or chassis, 9 having a mounting member 10 formed therefrom, which member is formed farther from the sheet 9 at the free end of the member than at the fixed end thereof. This arrangement is desirable since it allows a coil form 11 to be placed over the cantilever portion of the mounting member with the greatest of ease. The tip of member 10 is subsequently formed upwardly to engage one side of form 11 and thereby secure it firmly in place.

In some instances it is not permissible to have openings in a radio receiver chassis. In such cases a mounting member, such as that disclosed in Figures 7 and 8, may be employed in lieu of that previously described. The mounting lug 12 is formed in a shape similar to that disclosed in the preceding figures but has a portion formed parallel to a chassis 13, and adjacent thereto, at the fixed end of the lug 12. This portion of the lug 12 is preferably attached to the chassis 13 by spot welds 14.

Radio receiver chassis usually have several flat portions formed perpendicularly to each other. It is therefore possible to form a mounting lug from one of a pair of perpendicular flat portions, or walls, in order to secure a coil form to the other one of the flat portions, or walls. Such an arrangement has been illustrated in Figures 9 and 10 wherein a mounting lug 15 is formed from a sidewall of a chassis 16 parallel to a horizontal portion of such chassis. A coil form 17 is secured, with one end thereof in abutment with the horizontal portion of the chassis 16, in the same manner as described heretofore.

In Figure 11 a modified form of the mounting lugs previously described has been shown. In this modification the entire tip end of the lug has been reduced in width rather than merely providing a narrow constricted portion near the tip. In the appended claims it is intended that the term "neck portion" apply to either of the forms of tip disclosed herein.

While particular embodiments of the present invention have been shown and described, it will be obvious to those skilled in the art that changes and modifications may be made without departing from this invention in its broader aspects, and, therefore, the aim in the appended claims is to cover all such changes and modifications as fall within the true spirit and scope of this invention.

I claim:

1. In combination, a metallic sheet, a tubular coil form having one end abutting said sheet, said form having opposed openings therein spaced at equal distances from said one end, and a member extending from said sheet and having a portion extending parallel thereto, said member having a shoulder formed therein at the fixed end of the

parallel portion and having a neck portion formed therein at the free end of the parallel portion, the parallel portion of said member extending through said openings with said shoulder engaging one side of said form and having said neck portion formed over to engage the opposite side of said form.

2. In combination, a supporting sheet, a tubular coil form having one end abutting said sheet, said form having openings therein spaced from said one end, and a member extending from said sheet and having a cantilever portion, said member having a shoulder formed therein at the fixed end of the cantilever portion and having a weakened section at the free end of the cantilever portion, the cantilever portion of said member extending through said openings with said shoulder engaging one side of said form and having said weakened section formed over to engage the opposite side of said form.

3. In combination, a supporting sheet, a tubular coil form having one end abutting said sheet, said form having opposed openings therein spaced at equal distances from said one end, and a member formed from said sheet and having a portion extending parallel thereto, the parallel portion of said member extending through said openings to firmly secure the form to said sheet.

4. In combination, a supporting sheet, a tubular coil form having one end abutting said sheet, said form having openings therein spaced from said one end, and a member formed from said sheet and having a cantilever portion extending through said openings to firmly secure the form to said sheet.

5. In combination, a supporting sheet, a tubular coil form having one end abutting said sheet, said form having openings therein spaced from said one end, and a member extending from said sheet and having a cantilever portion extending through said openings to firmly secure the form to said sheet.

6. In combination, a supporting sheet, a tubular coil form having one end abutting said sheet, a member extending from said sheet and having a cantilever portion extending through said coil form, and means at the free end of the cantilever portion for preventing movement of said coil form relative to said member.

FRANK WOOD.
